UNITED STATES PATENT OFFICE.

HAROLD T. BLUM, OF AMHERST, OHIO.

ANTIREFILLABLE BOTTLE.

1,314,460.

Specification of Letters Patent. Patented Aug. 26, 1919.

Application filed March 9, 1915. Serial No. 13,179.

To all whom it may concern:

Be it known that I, HAROLD T. BLUM, a citizen of the United States, residing at Amherst, in the county of Lorain and State of Ohio, have invented certain new and useful Improvements in Antirefillable Bottles; and I do hereby declare the following to be a full, clear, and exact description of the invention, such as will enable others skilled in the art to which it appertains to make and use the same.

This invention relates to new and useful improvements in anti-refillable bottles and has for its principal object to provide a device of the above character which will prevent unauthorized persons from diluting the contents of bottles or from refilling the bottles after they have once been emptied.

Another object of the invention is to provide a device which will effectively protect the public from persons who are apt to fill a bottle and sell the same fraudulently.

Still another object of the invention is to provide a bottle which in case it is tampered with will show signs of such tampering.

With these and other objects in view, the invention consists in the novel combination and arrangement of parts which will be fully set forth in the following specification and accompanying drawing, in which—

Figure 1 is a vertical sectional view through a fragment of the bottle constructed in accordance with this invention.

Fig. 2 is a sectional view taken on line 2—2 of Fig. 1, and

Fig. 3 is a detail perspective view of one of the guard pins.

Referring now to the drawing, by characters of reference, the numeral 1 designates as an entirety a bottle of the usual construction comprising a body 2 having formed thereon the usual neck 3. This neck is formed with the enlarged opening 4 for the reception of the stopper 5 and the shoulder 6 is formed at the lower end of the enlarged opening and is provided with the tapered opening 7 forming a valve seat against which the ball valve which will be more fully hereinafter described rests. Molded in the bottle neck between the shoulder 6 and the point where the neck joins the bottle are the guard

pins designated generally by the numeral 8 which comprise the body 9 having the upturned end 10. The opposite end of this body is downturned as at 11 to form a guard 55 against which the ball valve rests when the bottle is in its inverted position. This ball valve is designated generally by the numeral 12 and comprises a spherical body 13 which is arranged to rest against the valve seat 7 60 and completely close the opening. The upturned ends 10 of the pins 9 extend into the grooves 14 in the bottle neck, and it will be apparent that in case any person tampers with the pins, the bottle neck will be broken 65 and thus indicate to the user the fact that an attempt has been made to substitute or place fraudulent or spurious material in the bottle.

While in the foregoing, there has been 70 shown and described the preferred embodiment of this invention, it is to be understood that such changes may be made in the combination and arrangement of parts as will fall within the spirit and scope of the 75 appended claim.

What is claimed is:

A bottle of the character described comprising a body and a neck, said neck being formed with a valve seat on its lower extremity and having a shoulder intermediate the ends to limit the downward movement of the bottle stopper when placed in the neck, a spherical valve arranged on the valve seat, said bottle neck provided with grooves 80 on the exterior thereof below the shoulder, a plurality of guard pins having horizontal portions embedded in the neck below the shoulder, the inner ends of said guard pins turned downwardly and limiting the movement of the spherical valve, the outer ends of said pins bent upwardly into the grooves thus preventing the pins from being removed without indicating to the user an attempt to remove the pins. 90 95

In testimony whereof I affix my signature in presence of two witnesses.

HAROLD T. BLUM.

Witnesses:

J. J. SMYTHE,
J. S. McCORMICK.
